REFRIGERATING MACHINE

Alexander R. Stevenson, Jr., Schenectady, N. Y.,
assignor to General Electric Company, a corporation of New York

Application December 5, 1934, Serial No. 756,095

23 Claims. (Cl. 62—136)

My invention relates to refrigerating machines of the type in which a gaseous refrigerant is utilized without liquefaction.

Refrigerating machines which circulate a gaseous refrigerant through the refrigerant cycle without liquefaction may comprise a high pressure refrigerant circuit and a low pressure refrigerant circuit, a device or devices to compress refrigerant received from the low pressure circuit and deliver it to the high pressure circuit, and to expand refrigerant received from the high pressure circuit and deliver it to the low pressure circuit. These devices may be combined in a single machine for performing both expanding and compressing operations. Such a combined machine is termed a wattless compressor since no net work is done on the refrigerant thereby. The expanded refrigerant and compressed refrigerant are delivered to the low and high pressure circuits respectively by scavenging pumps or fans arranged in the circuits. The compressed refrigerant is cooled in the high pressure circuit by a suitable heat exchanger and the expanded refrigerant in the low pressure circuit is utilized to absorb heat from a cooling element. The continuous operation of the expanding and compressing devices tends to equalize the pressures in the high and low pressure circuits and, in order to maintain the desired pressure difference between the circuits, a compressor or pump is provided which continually operates to pump refrigerant from the low pressure circuit to the high pressure circuit. This compressor is termed a power compressor. It has been proposed to construct a machine arranged to perform the functions of compression and expansion and of maintaining the pressure difference between the high and low pressure circuits. In the machines thus far proposed it has been necessary to provide pressure actuated ports through which the refrigerant must pass during the scavenging operation. Such an arrangement is undesirable because it produces excessive losses due to turbulence of the gas during the scavenging operation.

Accordingly, it is an object of my invention to provide an improved refrigerating machine of the type above referred to in which gaseous refrigerant is utilized without liquefaction which shall require only a single machine for performing all the functions of compression and expansion.

Another object of my invention is to provide a refrigerating machine utilizing a gaseous refrigerant without liquefaction, which shall perform the functions of a wattless and a power compres-

sor, and which shall provide an unobstructed path for the scavenging gases.

A further object of my invention is to provide a refrigerating machine utilizing a gaseous refrigerant without liquefaction incorporating an improved and well-balanced wattless compressor.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawings in which Fig. 1 is a diagrammatic view of a refrigerating machine embodying my invention; Fig. 2 is an enlarged sectional plan view of the compressor shown in Fig. 1; and Fig. 3 is a sectional view on the line 3—3 of Fig. 2.

Referring now to Fig. 1, I have shown a refrigerating machine including a compressor 10 having stationary cylinders 11 and 11a and provided with a driving motor 12. The compressor 10 is arranged to alternately expand and compress refrigerant, refrigerant being compressed in the cylinder 11 at the same time that refrigerant is being expanded in the cylinder 11a and vice versa. A high pressure refrigerant circuit and a low pressure refrigerant circuit are connected to the compressor. The high pressure circuit includes a heat exchanger or cooling coil 13 for cooling the hot compressed gas received from the compressor and a scavenging fan 14 for scavenging the cylinders 11 and 11a and replacing the hot compressed refrigerant therein with refrigerant at the same pressure which has been cooled in the coil 13. During the scavenging operation hot compressed gas is delivered from the cylinders alternately through conduits 16 and 16a to the conduit 15, and is circulated by the fan 14 through the coil 13 where it is cooled before returning through a conduit 17 and alternately through conduits 18 and 18a to the compressor, the path of the high pressure refrigerant being indicated by arrows. The low pressure circuit includes a refrigerating coil 19 arranged to cool any desired medium and a scavenging fan 20 for scavenging the cylinders 11 and 11a and replacing the cold expanded gas therein with refrigerant at substantially the same pressure warmed by passage through the coil 19. During the scavenging operation, cold expanded gas is delivered from the cylinders alternately through conduits 21 and 21a to the coil 19, and is warmed in the refrigerating coil 19 before being returned through a conduit 22.

- and alternately through conduits 23 and 23a to the compressor. The operation of the compressor 10 which supplies hot compressed gas to the high pressure circuit and cold expanded gas to the low pressure circuit tends to equalize the pressures in the circuits. In order to maintain the desired pressure difference between the circuits, the compressor 10 is constructed so that it will pump refrigerant from a connection 24 between the conduit 22 and the casing of the compressor in the low pressure circuit through connections 25 and 25a into the conduit 15 of the high pressure circuit, thereby maintaining the desired pressure difference.
- 15 Referring now to Fig. 2 of the drawings, the compressor 10 including the cylinders 11 and 11a is symmetrical the cylinder 11 and all parts of the compressor to the left of a shaft 26 driven by the motor 12 being similar to and symmetrical with the cylinder 11a and all parts of the compressor to the right of the shaft 26. In this description the symmetrical parts to the right of the shaft 26 have been designated by applying the letter *a* to the same numerals as the parts to the left thereof. The moving parts of the compressor are balanced, so that the equal masses at all times move in opposite directions and at equal rates of acceleration. Cylinders 27 and 27a are arranged within the cylinders 11 and 11a and pistons 28 and 28a are arranged to move within the cylinders 27 and 27a. Cylinders 27 and 27a are driven at the same rate and in the opposite direction from the pistons 28 and 28a, so that when one of the pistons is on its expansion stroke the other is on its compression stroke. The pistons and the cylinders are driven by Scotch yoke connections. As shown in Figs. 2 and 3, the driving mechanism for the cylinders 27 and 27a includes yokes 29 and 29a secured together by bolts 30 and blocks 31 arranged to slide transversely of the cylinder axis between guides 32 and 32a formed in the yokes 29 and 29a respectively. A reciprocating motion is imparted to the cylinders through eccentrics 33 driven by the shaft 26 and mounted in the blocks 31 on roller bearings 34 arranged between cages 35 and 36. A similar mechanism is provided for driving the pistons 28 and 28a and includes a yoke 37 formed integrally with the pistons 28 and 28a. Sliding blocks or cross-heads 38 are mounted in guides 39 and 39a in the sides of the yoke 37, and a reciprocating motion is imparted to the pistons by eccentrics 40 mounted in the blocks 38 and roller bearings 41 having inner bearing races 42 and outer bearing races 43. The eccentrics 33 and 40 are displaced 180° and have the same eccentricity, and the reciprocating mass including the cylinders 27 and 27a driven by the eccentrics 33 is the same as the reciprocating mass including the cylinders 28 and 28a driven by the eccentrics 40. As the eccentrics 33 and 40 are mounted 180° apart on the shaft 26, the pistons and cylinders are driven in opposite directions at equal rates of acceleration and the reciprocating forces are therefore balanced. Fly-wheels 44 are provided on the shaft 26 on either side of the Scotch yoke driving mechanism.
- 70 The compressor is shown with the cylinders 27 and 27a in their extreme left-hand positions and, consequently, with the pistons 28 and 28a in their extreme right-hand positions. The piston 28 is, therefore, at the end of its expansion stroke and in communication with the low pressure circuit, and the piston 28a is at the end of its com-

pression stroke, and in communication with the high pressure circuit.

The cylinder 27 is in communication with the low pressure circuit of the refrigerating machine through ports 45 and 46 connected to the low pressure conduits 23 and 21 respectively, and which register with ports 47 and 48 respectively in the cylinder 27 and with ports 49 and 50 in a cylindrical extension 51 on the piston 28. The scavenging fan 20 circulates low pressure gas 10 warmed in the coil 19 to cylinder 27 through the ports 49 and 50 and forces out cold expanded gas through the ports 48 into the conduit 21 through which it is conveyed to the refrigerating coil 19.

The cylinder 27a is in communication with the high pressure circuit through ports 52a and 53a communicating with the high pressure conduits 18a and 16a respectively and registering with ports 54a and 55a in the piston 27a and with ports 49a and 50a in extension 51 of the piston 20 28a. High pressure scavenging gas circulated by the fan 14 flows through the coil 13, is cooled therein and then flows through the conduit 18a through registering ports 52a, 54a and 49a and then through the cylinder 27 around a baffle 25 56a therein and forces the hot compressed gas out through the registering ports 50a, 55a and 53a and through conduit 16a to the conduit 15. The baffle 56a divides the space within the cylindrical extension 51 of the piston into a U-shaped 30 passage having a substantially uniform cross-sectional area. This arrangement whereby a baffle is provided within the cylinder to provide a passage of substantially uniform cross-sectional area for the scavenging gas is described 35 and claimed in a co-pending application of Robert U. Berry, Serial No. 756,111, filed December 5, 1934, and assigned to the General Electric Company, assignee of this present application. I do not, therefore, claim herein anything described 40 or claimed in the said Berry application which is to be regarded as prior art with respect to this present application, my present invention relating to an improved arrangement for combining the wattless and power compressors and for balancing the wattless compressor of a refrigerating machine utilizing gaseous refrigerant without liquefaction.

As has been pointed out, the operation within the right and left-hand cylinders 11 and 11a 50 is identical and, while one cylinder is compressing the other one is expanding the refrigerant gas. It will be evident, therefore, that when the cylinders 27 and 27a and the pistons 28 and 28a are at the opposite ends of their strokes, the cylinder 27 will be in communication with the high pressure circuit of the refrigerating machine and the cylinder 27a will be in communication with the low pressure circuit of the refrigerating machine. The scavenging of the compressed 60 and expanded gas for this opposite position of the cylinders and pistons is, therefore, the same as that explained above for the position shown in the drawings. These compressing and expanding operations will continue throughout the 65 operation of the compressor. A consideration of this operation will disclose that it tends to equalize the pressures between the high pressure and low pressure circuits. For example, when the hot compressed gas is replaced during 70 the scavenging operation with cool compressed gas, a greater weight of gas is left in the cylinder than was present at the end of the compression stroke. This cooled gas is then expanded and delivered on the next scavenging 75

operation to the low pressure circuit when it is replaced by warmer low pressure gas. A greater weight of gas is thus added to the low pressure circuit than is taken therefrom. A repetition 5 of this operation results in a continual drain of refrigerant from the high pressure circuit to the low pressure circuit. For this reason, it is necessary to provide an arrangement for returning refrigerant from the low pressure circuit to 10 the high pressure circuit in order to maintain the desired difference in pressure between said circuits.

In accordance with my invention I provide additional ports in the cylinders 27 and 27a and 15 utilize the movement of the pistons 28 and 28a to pump refrigerant directly from the low pressure circuit to the high pressure circuit when the cylinders and pistons are intermediate their scavenging positions.

20 In the illustrated embodiment of my invention shown in Fig. 2 I provide normally closed pressure operated valves or ports 57 and 57a in heads 58 and 58a of the cylinders 27 and 27a respectively. These valves are designed to open when 25 the pressure within the cylinders 27 and 27a exceeds the pressure in the high pressure circuit by a predetermined amount, the high pressure circuit being connected with chambers 59 and 59a in the ends of the cylinders 11 and 11a by 30 the conduits 25 and 25a. I also provide pressure operated valves 60 and 60a for providing communication between the cylinders 27 and 27a and the low pressure circuit when the pressure therein is a predetermined amount less than the pressure 35 within the low pressure circuit. The valves 60 and 60a are arranged at the ends of passages 61 and 61a in the pistons 28 and 28a. In order to provide communication between the low pressure circuit and the passages 61 and 61a, I enclose 40 the Scotch yoke driving mechanisms within a sealed casing comprising a housing 62 and end plates 63 and 63a formed integrally with the cylinders 11 and 11a respectively, the connection 24 and a plurality of ducts 64 providing communication 45 between the low pressure circuit and the interior of the housing 62. It will be seen from a consideration of Fig. 3 that the refrigerant is free to pass through the spaces between the blocks 31 and the yokes 29 and 29a. In order 50 to provide communication between the interior of the housing 62 and passages 61 and 61a, I provide ducts 65 and 65a respectively in the yokes 31.

When the piston 28 and the cylinder 27 are 55 moved from the right hand position in which they are shown, the ports 45 and 46 in the cylinder 11 are closed by movement of the cylinder 27, and the compression of the gas within this cylinder begins. The pressure within the cylinder 27 becomes equal to that within the high 60 pressure circuit before the piston reaches the end of its stroke. The pressure, therefore, increases above the pressure of the high pressure circuit and a volume of gas is forced out through 65 the valve 57 into the chamber 59 and thence through the conduit 25 to the high pressure circuit. The cylinder 27 and piston 28 then reach the ends of their strokes and open the ports 52 and 53, and the pressure between the cylinder 27 and the high pressure circuit is equalized during 70 the scavenging operation. On the return stroke the ports 52 and 53 are closed and the gas in the cylinder is expanded until its pressure becomes less than that within the low pressure circuit. Further movement of the cylinder and

piston will then tend to further decrease this pressure and will draw refrigerant into the cylinder 27 through the valve 60 from the housing 62 communicating with the low pressure circuit, thereby increasing the amount of gas within the cylinder 27. On the scavenging operation the pressure within the cylinder 27 and the low pressure circuit will be equalized due to the opening of the ports 45 and 46, and the compression cycle will be repeated. From the foregoing it is seen 10 that by operation of the piston 28 and the cylinder 27 gas is continuously removed from the low pressure circuit and pumped by the piston 28 into the high pressure circuit through the valves 60 and 57 respectively. The pumping operation 15 on the right end of the compressor within the cylinder 27a is exactly the same as that just described within the cylinder 27, the valves 51a and 60a operating in the same manner as the valves 57 and 60. From a consideration of the 20 operation of the compressor it will clearly be seen that the power and wattless compressors have been combined in one machine, and that the scavenging operations are performed without the necessity for the passage of scavenging gas 25 through the pressure operated valve or the like, and that the function of maintaining the pressure difference between the high and low pressure circuits is performed by the machine through ports separate from the ports utilized during the 30 scavenging operation. The difference in pressure between the high and low pressure circuit is determined by the dimensions of the cylinders 27 and 27a and of the pistons 28 and 28a; and by proper design a refrigerating machine may be 35 provided to operate at any desired pressure difference.

During operation of the refrigerating machine shown in Fig. 1 the cooling coil 13 is arranged to be cooled by a fluid such as water or air 40 circulating thereover. The coil 13 is placed in a refrigerator cabinet, or in contact with any medium to be cooled. The compressor 10 is operated continuously or at intervals, as desired to maintain the required temperature of the coil 13. 45 The scavenging fans 14 and 20 operate continuously during operation of the compressor 10.

From the foregoing it is apparent that I have provided an improved refrigerating machine utilizing a gaseous refrigerant without liquefaction 50 and embodying a balanced compressor for performing all the functions of compression, expansion and maintenance of pressure difference in the system.

While I have described one embodiment of my 55 invention, I do not desire my invention to be limited to the particular construction shown and described, and I intend in the appended claims to cover all modifications within the spirit and scope of my invention.

What I claim as new and desire to secure by Letters Patent of the United States, is:—

1. A refrigerating machine of the type utilizing a gaseous refrigerant without liquefaction comprising a low pressure refrigerant circuit and a 65 high pressure refrigerant circuit, means including a cylinder having high and low pressure intake and exhaust ports and a piston movable therein for compressing refrigerant from said low pressure circuit and for expanding refrigerant from said high pressure circuit, scavenging means for utilizing said high and low pressure ports for circulating gas compressed in said cylinder through said high pressure circuit and for circulating gas expanded in said cylinder through 70 75

8. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke, means arranged in said low pressure circuit and utilizing the cooling effect of the scavenged expanded gas for producing refrigeration, means utilizing said high pressure circuit for scavenging said cylinder at the end of said compression stroke, means arranged in said high pressure circuit for cooling the scavenged compressed gas, and means including ports in said cylinder in addition to said above-mentioned ports and utilizing the movement of said piston for maintaining a difference in pressure between said circuits.

9. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke, means utilizing said high pressure circuit for scavenging said cylinder at the end of said compression stroke, and means including a port in said piston and an additional port in said cylinder and utilizing the movement of said piston for maintaining a difference in pressure between said circuits.

10. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke, means utilizing said high pressure circuit for scavenging said cylinder at the end of said compression stroke, and means including ports in addition to said first mentioned ports for withdrawing gas from said low pressure circuit prior to scavenging expanded gas from said cylinder and for adding gas to said high pressure circuit prior to scavenging compressed gas from said

cylinder to maintain a difference in pressure between said circuits.

11. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder actuated by said piston for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke, means utilizing said high pressure circuit for scavenging said cylinder at the end of said compression stroke, means including a pressure operated port arranged in said piston for withdrawing refrigerant from said low pressure circuit prior to the scavenging of expanded gas from said cylinder, and means including a pressure operated port arranged in said cylinder for adding refrigerant to said high pressure circuit prior to the scavenging compressed gas from said cylinder to maintain a difference in pressure between said circuits.

12. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke, means utilizing said high pressure circuit for scavenging said cylinder at the end of said compression stroke, a driving connection for said piston, a closed casing surrounding said driving connection and communicating with said low pressure circuit, and means utilizing the movement of said piston and including a port in said cylinder communicating with said casing and a port in addition to said above mentioned ports communicating with said high pressure circuit for pumping refrigerant from said low pressure circuit to said high pressure circuit to maintain a difference in pressure between said circuits.

13. A refrigerating machine of the type utilizing a gaseous refrigerant without liquefaction comprising a low pressure refrigerant circuit and a high pressure refrigerant circuit, means including a cylinder and a piston movable therein for expanding refrigerant on one stroke of said piston and for compressing refrigerant on the other stroke thereof, means including ports in said cylinder for providing communication between said cylinder and said low pressure circuit at the end of the expansion stroke of said piston and for providing communication between said cylinder and said high pressure circuit at the end of the compression stroke of said piston, means utilizing said low pressure circuit for scavenging said cylinder at the end of said expansion stroke,

means utilizing said high pressure circuit for scavenging said cylinder at the end of said compression stroke, a driving connection for said piston, a closed casing surrounding said driving connection and communicating with said low pressure circuit, means including a port arranged in said piston for withdrawing refrigerant from said casing prior to the scavenging of said cylinder at the end of said expansion stroke, and

5 means including a port in said cylinder separate from said above mentioned ports for adding refrigerant to said high pressure circuit prior to the scavenging of said cylinder at the end of the compression stroke of said piston.

10 15. 14. A refrigerating machine of the type utilizing a gaseous refrigerant without liquefaction comprising a low pressure refrigerant circuit and a high pressure refrigerant circuit, a stationary cylinder having high pressure ports communicating with said high pressure circuit and low pressure ports communicating with said low pressure circuit, a second cylinder reciprocatable between two extreme positions in said stationary cylinder, said second cylinder having high pressure ports

20 25 communicating with the high pressure ports in said stationary cylinder in one extreme position of said second cylinder and having low pressure ports communicating with the low pressure ports of said stationary cylinder in the other extreme position of said second cylinder, a piston in said second cylinder reciprocatable with respect thereto, means including a driving mechanism for said piston and said second cylinder for compressing refrigerant from said low pressure circuit and for expanding refrigerant from said high pressure circuit, means utilizing said low pressure circuit for scavenging expanded refrigerant from said second cylinder in said other extreme position, means utilizing said high pressure

30 35 40 circuit for scavenging compressed refrigerant from said cylinder in said one extreme position, and means for maintaining a difference in pressure between said circuits.

15. A refrigerating machine of the type utilizing a gaseous refrigerant without liquefaction comprising a low pressure refrigerant circuit and a high pressure refrigerant circuit, a stationary cylinder having high pressure ports communicating with said high pressure circuit and low pressure ports communicating with said low pressure circuit, a second cylinder reciprocatable between two extreme positions in said stationary cylinder, said second cylinder having high pressure ports

45 50 55 communicating with the high pressure ports in said stationary cylinder in one extreme position of said second cylinder and having low pressure ports communicating with the low pressure ports of said stationary cylinder in the other extreme position of said second cylinder, a piston in said second cylinder reciprocatable with respect thereto, means including a driving mechanism for said piston and said second cylinder for compressing refrigerant from said low pressure circuit and for expanding refrigerant from said high pressure

60 65 70 circuit, means utilizing said low pressure circuit for scavenging expanded refrigerant from said second cylinder in said other extreme position, means utilizing said high pressure circuit for scavenging compressed refrigerant from said cylinder in said one extreme position, and means including an additional port in said second cylinder communicating with said high pressure circuit and an additional port in said piston communicating with said low pressure circuit for pumping refrigerant from said low pressure circuit

75

cuit to said high pressure circuit to maintain a difference in pressure between said circuits.

16. A refrigerating machine of the type utilizing a gaseous refrigerant without liquefaction comprising a low pressure refrigerant circuit and a high pressure refrigerant circuit, a stationary cylinder having high pressure ports communicating with said high pressure circuit and low pressure ports communicating with said low pressure circuit, a second cylinder reciprocatable between two extreme positions in said stationary cylinder, said second cylinder having high pressure ports communicating with the high pressure ports in said stationary cylinder in one extreme position of said second cylinder and having low pressure ports communicating with the low pressure ports of said stationary cylinder in the other extreme position of said second cylinder, a piston in said second cylinder reciprocatable with respect thereto, means including a driving mechanism for said piston and said second cylinder for compressing refrigerant from said low pressure circuit and for expanding refrigerant from said high pressure circuit, means utilizing said low pressure circuit for scavenging expanded refrigerant from said second cylinder in said other extreme position, means utilizing said high pressure circuit for scavenging compressed refrigerant from said second cylinder in said one extreme position, and means including a pressure operated port in said piston and a pressure operated port in said second cylinder and utilizing the movement of said piston for maintaining a difference in pressure between said circuits.

17. A refrigerating machine of the type utilizing a gaseous refrigerant without liquefaction including a pair of oppositely disposed cylinders having pistons therein for alternately compressing and expanding refrigerant received from said low pressure refrigerant circuit and said high pressure refrigerant circuit respectively, means providing communication between said cylinders and said low pressure circuit for scavenging expanded refrigerant from said cylinders, means providing communication between said cylinders and said high pressure circuit for scavenging compressed refrigerant from said cylinders, a driving mechanism for said pistons arranged therebetween, a casing enclosing said driving mechanism and communicating with said low pressure circuit, and means including ports in said cylinders for pumping refrigerant from said casing to said high pressure circuit to maintain a difference in pressure between said circuits.

18. A refrigerating machine of the type utilizing a gaseous refrigerant without liquefaction including a pair of oppositely disposed cylinders, a pair of pistons arranged in said cylinders and reciprocatable relatively thereto, and means including a driving mechanism arranged between said cylinders for alternately compressing and expanding refrigerant in said cylinders, means providing communication between said cylinders and said low pressure circuit for scavenging expanded refrigerant from said cylinders, means providing communication between said cylinders and said high pressure circuit for scavenging compressed refrigerant from said cylinders, a casing enclosing said driving mechanism and communicating with said low pressure circuit, and means separate from said scavenging means for pumping refrigerant from said casing to said high pressure circuit to maintain a difference in pressure between said circuits.

19. A refrigerating machine of the type utl-75

- lizing a gaseous refrigerant without liquefaction including a pair of cylinders spaced apart and arranged in alignment, a pair of pistons arranged within said cylinders, means including a driving mechanism arranged between said cylinders and between said pistons for driving said pistons and said cylinders, said pistons moving in unison in a direction opposite to that of said cylinders, means including ports in said cylinders registering with said high pressure circuit at the end of the compression strokes of said cylinders for scavenging compressed gas from said cylinders, means including ports in said cylinders registering with said low pressure circuit at the end of the expansion strokes of said pistons for scavenging expanded gas from said cylinders, a sealed casing enclosing said driving mechanism and communicating with said low pressure circuit, and means including ports in said cylinders in addition to said above mentioned ports for pumping refrigerant from said casing to said high pressure circuit to maintain a difference in pressure between said circuits.
20. A refrigerating machine of the type utilizing a gaseous refrigerant without liquefaction including a pair of cylinders arranged in alignment, a pair of pistons arranged within said cylinders, means including a driving mechanism associated with said pistons and a driving mechanism associated with said cylinders for reciprocating said pistons and said cylinders and for simultaneously displacing them equally in opposite directions, said pistons and said driving mechanism associated therewith having the same mass as said cylinders and said driving mechanism associated therewith so as to balance said mechanism, means including ports in said cylinders registering with said high pressure circuit on the compression strokes of said pistons for scavenging compressed gas from said cylinders, and means including ports in said cylinders registering with said low pressure circuit on the expansion stroke of said pistons for scavenging expanded gas from said cylinders.
45. 21. A refrigerating machine of the type utilizing a gaseous refrigerant without liquefaction including a pair of cylinders arranged in alignment, a pair of pistons arranged within said cylinders, means including a driving mechanism associated with said pistons and a driving mechanism associated with said cylinders for reciprocating said pistons and said cylinders and for simultaneously displacing them equally in opposite directions, said pistons and said driving mechanism associated therewith having the same mass as said cylinders and said driving mechanism associated therewith so as to balance said mechanism, means including ports in said cylinders registering with said high pressure circuit on the compression strokes of said pistons for scavenging compressed gas from said cylinders, means including ports in said cylinders registering with said low pressure circuit on the expansion stroke of said pistons for scavenging expanded gas from said cylinders, a sealed casing enclosing said driving mechanisms and communicating with said low pressure circuit, and means for pumping refrigerant from said low pressure circuit to said high pressure circuit to maintain a difference in pressure between said circuits.
- from said cylinders, means including ports in said cylinders registering with said low pressure circuit on the expansion stroke of said pistons for scavenging expanded gas from said cylinders, a sealed casing enclosing said driving mechanisms and communicating with said low pressure circuit, and means utilizing said pistons for pumping refrigerant from said low pressure circuit to said high pressure circuit to maintain a difference in pressure between said circuits.
22. A refrigerating machine of the type utilizing a gaseous refrigerant without liquefaction including a pair of cylinders spaced apart and arranged in alignment, a pair of pistons arranged within said cylinders, means including a driving mechanism arranged between said cylinders and a driving mechanism arranged between said pistons for reciprocating said pistons and said cylinders and for simultaneously displacing them equally in opposite directions, said pistons and said driving mechanism arranged therebetween having the same mass as said cylinders and said driving mechanism arranged therebetween so as to balance said machines, means including ports in said cylinders registering with said high pressure circuit on the compression strokes of said pistons for scavenging compressed gas from said cylinders, and means including ports in said cylinders registering with said low pressure circuit on the expansion stroke of said pistons for scavenging expanded gas from said cylinders.
25. 23. A refrigerating machine of the type utilizing a gaseous refrigerant without liquefaction including a pair of cylinders spaced apart and arranged in alignment, a pair of pistons arranged within said cylinders, means including a driving mechanism arranged between said cylinders and a driving mechanism arranged between said pistons for reciprocating said pistons and said cylinders and for simultaneously displacing them equally in opposite directions, said pistons and said driving mechanism arranged therebetween having the same mass as said cylinders and said driving mechanism arranged therebetween so as to balance said machine, means including ports in said cylinders registering with said high pressure circuit on the compression strokes of said pistons for scavenging compressed gas from said cylinders, means including ports in said cylinders registering with said low pressure circuit on the expansion stroke of said pistons for scavenging expanded gas from the cylinders, a sealed casing enclosing said driving mechanisms and communicating with said low pressure circuit, and means for pumping refrigerant from said low pressure circuit to said high pressure circuit to maintain a difference in pressure between said circuits.

ALEXANDER R. STEVENSON, JR. 60
